(57) **CLAIM**

The ornamental design for a liner for respirator mask, as shown and described.

DESCRIPTION

FIG. 1 is a front view of a liner for a respirator mask according to an embodiment, the rear view being identical thereto;

FIG. 2 is a right side view of the liner for respirator mask of FIG. 1, the left side view being identical thereto;

FIG. 3 is a top view of the liner for respirator mask of FIG. 1, the bottom view being identical thereto;

FIG. 4 is a front view of a liner for a respirator mask according to another embodiment, the rear view being identical thereto;

FIG. 5 is a right side view of the liner for respirator mask of FIG. 4, the left side view being identical thereto;

FIG. 6 is a top view of the liner for respirator mask of FIG. 4, the bottom view being identical thereto;

FIG. 7 is a front view of a liner for a respirator mask according to another embodiment, the rear view being identical thereto;

FIG. 8 is a right side view of the liner of FIG. 7, the left side view being identical thereto; and,

FIG. 9 is a top view of the liner for respirator mask of FIG. 7, the bottom view being identical thereto.
